(57) **CLAIM**

The ornamental design for an air moving device, as shown
and described.

DESCRIPTION

FIG. 1 is a front, left, and top side perspective view of an air
moving device embodying our new design;

FIG. 2 is a front side elevational view thereof;

FIG. 3 is a back side elevational view thereof;

FIG. 4 is a left side elevational view thereof;

FIG. 5 is a right side elevational view thereof; and,

FIG. 6 is a top plan view thereof.

Broken lines are used to illustrate features of the air moving
device which form no part of the claimed design. Dot-dash
lines are used to illustrate boundary lines and form no part
of the claimed design.
